UNITED STATES PATENT OFFICE

EARL P. HARTRY, OF DETROIT, MICHIGAN, ASSIGNOR OF ONE-HALF TO RUSSELL SABOR,
OF MINNEAPOLIS, MINNESOTA

DESIGN FOR AN AUTOMOBILE BODY

Application filed October 24, 1928. Serial No. 28,610. Term of patent 14 years.

To all whom it may concern:

Be it known that I, EARL P. HARTRY, a citizen of the United States, residing at Detroit, county of Wayne, and State of Michigan, have invented a new, original, and ornamental Design for an Automobile Body, of which the following is a specification, reference being had to the accompanying drawings, forming part thereof.

Fig. 1 is a side elevation of the article showing my new design.

Fig. 2 is a front elevation.

Fig. 3 is a sectional plan.

Fig. 4 is a rear elevation.

The hood, radiator, lamps, fenders and wheels being shown in dotted lines.

I claim:

The ornamental design for an automobile body, as shown.

EARL P. HARTRY.
